UNITED STATES PATENT OFFICE.

BENJAMIN F. GEORGE, OF POTOMAC, ILLINOIS, ASSIGNOR OF ONE-HALF TO
WILLIAM H. BELLES, OF POTOMAC, ILLINOIS.

HARNESS-BUCKLE.

SPECIFICATION forming part of Letters Patent No. 714,171, dated November 25, 1902.

Application filed May 15, 1902. Serial No. 107,476. (No model.)

to all whom it may concern:

Be it known that I, BENJAMIN F. GEORGE, a citizen of the United States, residing at Potomac, in the county of Vermilion and State of Illinois, have invented a new and useful Harness-Buckle, of which the following is a specification.

This invention has for its object a buckle employed in connection with harness, more particularly with the buckles usually employed to connect the traces to the other parts of the harness and also to connect the back-bands and girth-bands to the trace-supporting means.

The invention consists in certain novel features of the construction, as hereinafter shown and described, and specified in the claims.

In the drawings illustrative of the invention, Figure 1 is a side view of a portion of the back-band, the girth, and the trace of a harness with one of the improved buckles attached thereto. Fig. 2 is an enlarged longitudinal sectional elevation on the line II of Fig. 1. Fig. 3 is a plan view of the buckle disconnected.

In the description following when mention is made of the "front" of the buckle it will be understood that the part toward the head of the horse is referred to.

The buckle comprises an oblong framework consisting of side members 10 and 10^a, an upwardly-rising loop-bar 10^b at the rear end, a relatively slightly-elevated loop-bar 10^c at the front end, side loops 10^d 10^e rising from the side members 10 10^a, a transverse bar 10^f connecting the side members 10 and 10^a centrally of the loops 10^d 10^e and in alinement with the side members 10 10^a and also in alinement with the bottom sides of the loops 10^d 10^e and having a centrally-disposed pin 10^h extending outwardly therefrom, and a transverse bar 10^g between the forward ends of the loops 10^d 10^e and in alinement with the forward ends of the side loops.

The parts above described are all formed in one single piece or casting, preferably of malleable iron or steel.

Loosely engaging the front bar 10^c is a clamp-frame consisting of a rear transverse bar 11, having a downwardly-extending pin

11^a, and a front transverse bar 11^b, connected to the bar 11 by curved side bars 11^c and 11^d. Rising from the ends of the curved bars 11^c 11^d at their juncture with the lower transverse bar 11^b are standards 11^e 11^f, connected at their upper ends by a transverse bar 11^g. This clamp-frame is adapted to engage the transverse bar 10^c with the bars 11 11^g, projecting outward beyond the line of the bar 10^c, while the bar 11^b extends transversely of the buckle below the line of the bar 10^c, as shown in Fig. 2. A portion of the back-band is shown at 12 extending through the loops 10^d 10^e and engaged by the pin 10^h and 60 projecting downward below the loop 10^e and affording means for the connection of the girth-band in the usual manner, the girth-band not being shown, as its construction is so well known and as it forms no part 70 of the present invention. The back-band will be provided with the usual perforations 12^a, spaced apart and affording means for its adjustment vertically upon the pin 10^h, as will be readily understood. The loops 10^d 75 10^e will be of just sufficient width to permit the back-band to move freely through them and will serve to retain the back-band in engagement with the pin 10^h. The bar 10^g, coming in line with the forward ends of the loops 10^d 10^e, serves as a guide to the side of the back-band as well as a support for the trace, as hereinafter shown.

The trace is represented at 13 of the usual construction, the portion 13^a, which leads to 85 the hames or breast-strap, being looped by its rearward end to the bar 11^d and the main trace 13, which leads to the singletree, being passed by its outer end beneath the bar 10^b, over the bar 10^g, and incidentally over the 90 back-band between the loops 10^d 10^e, beneath the bar 11, outside the bar 10^c, and beneath the bar 11^g and thence beneath the usual "keepers" 13^b on the short trace 13^a. The trace when thus arranged and the draft force 95 applied is pressed downward upon the back-band 12 and holds the latter in engagement with its pin 10^h and prevents displacement in coaction with the loops 10^d 10^e. When the draft force is applied, the tendency is for the 100 clamp-frame to be drawn in close engagement with the trace and clamp it down firmly in

- engagement with the bar 10^c, bending it over this bar, and thereby greatly increasing the holding force by materially increasing the friction, and the greater the force of the draft 5 the more tightly the parts will be drawn together. The curved form of the side members 11^c 11^d greatly assist in this action, as they produce a somewhat rolling motion upon the bar 10^c as they are drawn beneath it.
- 10 The "grip" of the clamp-frame is sufficient to retain the trace 13 in engagement with the bar 10^c by friction alone against the ordinary draft of the team; but by providing the bar 11 with the pin 11^a the coupling between the 15 clamp-frame and the trace is rendered entirely secure with no possible chance for slipping, and thereby forming a positive coupling means between the parts.
- 20 The curved bars 11^c 11^d form a constantly decreasing fulcrum engagement between the transverse bar 10^c and exert a very strong leverage upon the trace, which increases in strength with any increase in the force of the draft. This curving of the bars 11^c 11^d of the 25 clamp-frame is therefore a very important feature of the invention, as it adjusts the leverage of the clamp-frame automatically to the requirements of the buckle by increasing the leverage correspondingly with any increase of strain.
- 25 The buckle may be made of any required size or strength and of any required material and ornamented in any desired manner, either by japanning, plating, or otherwise treating it.
- 30 If required, the bar 10^b may be provided with an extra loop 10^d to serve as a support for the holdback-strap.
- 35 The bar 11^e serves an important purpose, as it coacts with the bar 11 and curved side 40 bars 11^c 11^d to bend the trace 13 over the bar

10^c, and thereby greatly increase the grip of the buckle and minimizing any tendency to slip.

Having thus described my invention, what I claim is—

1. In a harness-buckle, a framework comprising a transverse front bar and a transverse rear bar over which the trace is adapted to pass, a clamp-frame comprising a transverse bar to which the rear end of the short 50 tag is adapted to be attached, and a transverse bar above the trace in the rear of said front bar, and having downwardly-curving side bars connecting the ends of said clamp-bars beneath said front bar, standards rising 55 from the lower front ends of said curved side bars and connected above the trace by a transverse front bar, substantially as described.

2. In a harness-buckle, a rectangular framework adapted to support the trace thereover, 60 a loop at the rear end adapted to engage the upper side of the trace and retain it in engagement with the framework, spaced bars upon opposite sides of the front member of said framework adapted to engage the upper 65 side of said trace, and inwardly-curving side bars connecting the ends of said spaced bars beneath said front member, and a transverse bar connecting said curved bars beneath the trace and adapted to support the rear end of 70 the short trace, substantially as described.

In testimony that I claim the foregoing as my own I have hereto affixed my signature in the presence of two witnesses.

his
BENJAMIN F. X. GEORGE.
